FOUNTAIN PEN

Edward Hugetz, New York, N. Y.

Application February 28, 1933, Serial No. 658,892

2 Claims. (Cl. 120—46)

This invention relates to improvements in fountain-pens, as they are for instance described in my Patent No. 1,918,844 issued July 18, 1933, of which this is a division in part.

It is one of the objects of this invention to provide a fountain-pen comprising a one piece barrel containing an ink sac filling the entire inner space of the barrel and having a substantially circular circumferential restricted portion intermediate its ends to provide an upper and a lower portion, while an air tube in its lower portion which, if it is flexible, may extend partly also into its upper portion, the restricted portion of the inner sac to be compressed by a lever acting upon a spring actuated pressure plate; thus the repeated operation of the lever and pressure plate will fill the sac so as to occupy, particularly with its lower portion the entire inner space of the fountain-pen barrel to hold a quantity of ink surpassing any quantity of ink which can be carried by barrels of equal or the same size of fountain pen barrel.

It will be understood that the pressure plate may be operated by other means than a laterally displaceable lever, as for instance by a button at the upper end of the barrel or by other suitable means.

These and other objects and advantages of my invention will become more fully known as the description proceeds and will then be specifically defined in the appended claims.

In the accompanying drawing forming a material part of this disclosure:

Fig. 1 is a longitudinal sectional view of a fountain pen constructed according to my invention.

Fig. 2 is a view similar to Figure 1 with the ink sac compressed.

As illustrated the pen consists of one piece barrel 10, into the lower part of which the ink feed 11 is inserted carrying the writing pen 12.

The ink sac 13 is provided about its middle with a restricted part 14 so as to form an upper portion 15 and a comparatively larger lower portion 16.

An air tube 17, preferably of a flexible material is slipped at its lower end over the extension 18 of the ink feed 11 as at 19, and extends with

its upper end for a limited distance into the upper portion 15 of the ink sac, as at 20.

A spring 21 is arranged as shown in the upper part of the barrel and a pressure plate 22 under the action of said spring and a pressure lever 23 pivoted intermediate of its ends, as at 24 serves to compress the upper portion 15 of the ink sac, as shown in Figure 2 and the upper end of the flexible air tube.

In operation on the release of the pressure plate 10 the ink sac sucks up the ink which operation is repeated until the sac is sufficiently filled, and it will be clear that the inflated ink sac is of such comparatively large diameter particularly at its lower portion as to fill out the entire 15 space of the inside of the fountain pen barrel and thus I create the largest possible space for the ink to hold a quantity of ink surpassing any quantity of ink which can be carried by fountain pen barrels of equal capacity or the 20 same size.

It will be understood that I have described and shown the preferred forms of my invention only as a few examples of the many possible ways to practically construct my invention and that I may make such changes therein as come within the scope of the appended claims without departure from the spirit of my invention and the principles involved.

Having thus described my invention what I 30 claim as new and desire to secure by Letters Patent is:

1. A fountain pen including its feed and comprising an ink sac in its barrel having a substantially circular circumferential restricted portion intermediate its ends, a lever actuated pressure plate shorter than the ink sac, and an air tube within said ink sac said ink sac adapted to be engaged by said pressure plate upon the operation of its lever.

2. A fountain pen including its feed and comprising an ink sac in its barrel, restricted intermediate its ends to form two comparatively large ink receiving chambers, a pressure plate and lever to operate the same, said pressure plate engaging one of the chambers of the ink sac, and a flexible air tube extending beneath said pressure plate.

EDWARD HUGETZ.
